JOSEPH J. RING, OF MILWAUKEE, AND CARL SCHINDLER, OF WEST ALLIS, WISCONSIN, ASSIGNORS TO ALLIS-CHALMERS MANUFACTURING COMPANY, OF MILWAUKEE, WISCONSIN, A CORPORATION OF DELAWARE.

CONTROL SYSTEM FOR PRIME MOVERS.

Application filed December 22, 1928. Serial No. 682,212.

This invention relates to control systems for prime movers.

In order to save the expense of attendants, it is desirable, in installations where this is feasible, to provide automatic means for starting and stopping a prime mover and controlling the same while it is running. It is one of the objects of this invention to provide such a system, the prime mover being started either from a remote point by a single manual operation or in response to a predetermined condition. Another object of the invention is to so control the prime mover in such a system that not more than a predetermined limited amount of power may be generated thereby.

A further object of the invention is the provision of a remote control or automatic control system for prime movers which will be in readiness to start at substantially all times. Still another object is the provision of an automatic control system in which the various operations will be carried out without the intervention of an operator in the proper sequence and with certainty. Other objects will appear hereinafter as the description of the invention proceeds.

The novel features of this invention will appear from the specification and the accompanying drawing forming a part thereof and disclosing one embodiment of said invention and all these novel features are intended to be pointed out in the claims.

The single figure of the drawing is a diagrammatic representation of the manner in which the invention may be applied to the control of a hydraulic turbine.

In the drawing, a turbine 1 drives a shaft 2 which may be connected, for example, to an electric generator (not shown). The admission of water to the turbine 1 is controlled by a valve 3 mounted on a pivot 4. It is of course to be understood that the representation of the valve 3 is diagrammatic and that the turbine may be controlled by other means such as guide vanes as is well known to those skilled in the art. The valve 3 may be turned by means of a crank 5 mounted on the pivot 4. The crank 5 is here shown as operable by a connecting rod 6 connected to a piston rod 7 which is associated with, in the instance shown, two pistons

8, 9. These pistons operate in a cylinder 10 divided into two compartments or cylinders 11, 12. The pistons 8, 9 with their cylinders 55 and necessary adjuncts constitute a servomotor for controlling the valve 3, and this motor is part of a governor to be hereinafter described.

The admission of fluid under pressure 60 (usually oil) to the cylinders 11, 12, is controlled by a regulating valve 13 comprising a cylinder 16 in which are movable the valve members 14, 15. A pipe 17 forms a connection between the cylinder 11 and the cylinder 16, and the port of this pipe in cylinder 16 is adapted to be controlled by the valve member 15. In a similar manner the pipe 18 connects the cylinder 12 with cylinder 16 and the port of this pipe is adapted to be 70 controlled by valve member 14. The valve members 14, 15 are shown as rigidly mounted on a rod 19 connected in a manner to be described to a floating lever 20 pivoted at 21 at the end of a spindle 22. As is usual in governors, the spindle 22 may be raised and lowered by centrifugal or speed responsive means. In the instance shown it is intended that a drop in speed will raise spindle 22 and a rise will lower it. As is well known to 75 those skilled in the art such speed responsive means may be driven in any suitable manner from the shaft of the turbine or other prime mover, and for the sake of clearness the speed responsive means has not been shown. 80 A dash pot or compensating device 23 of usual or suitable form is connected to the other end of the floating lever 20. The compensating device may for example be of the form shown in the patent to Englesson 85 1,126,433, Jan. 26, 1915. The compensating device 23 is here shown as operated by a rod 24 connected through a bell crank lever 25 and a rod 26 to a crank 27 mounted rigidly on the pivot 4, so that movement of the valve 95 3 will react on the governor in the usual manner.

The connection of the regulating valve 13 to the floating lever 20 includes a spring 28 one end of which acts against the end 29 of 100 a tube 31 and the other end against an end stop 30 on a rod 32 passing through end 29. Rod 32 is slidable through a block 33 pivotally mounted on floating lever 20. The end

of rod 32 is provided with an adjustable nut 34 acting against top of block 33. A spring 120 acts against the bottom of block 33 and against a collar 121 mounted on rod 32. At 5 its lower end tube 31 is fastened to rod 19.

Fluid under pressure is supplied to the cylinder 16 of the regulating valve 13 through a pipe 35 connected to a pressure tank 36 adapted to contain oil under pressure. The pipe 35 is connected to the cylinder 16 substantially mid way between the ports 17, 18. Suitable drains 122, 123 may be provided above and below valve members 14, 15 respectively. Pressure is placed upon 10 the fluid in tank 36 by means of a pump 37, drawing fluid from a sump, not shown. The pump 37 is here shown as driven by an electric motor 38, connected as will be herein-after described. A check valve 39 may be 15 inserted between the pump 37 and tank 36 so that when the pump 37 stops, the pressure in the tank will not be gradually lost.

The piston rod 7 is here shown as provided with a collar 40 rigidly associated therewith and this collar is provided with a notch 41 adapted to be engaged by a pawl 42 pivoted at 44. The pawl 42 may be lifted out of the notch 41 by means of a crank 43. In the position shown in the 20 drawing the piston 8 has moved the valve 3 to its closed position and the pawl 42 has engaged the notch 41. In this position therefore the pawl prevents the movement of the piston rod 7 in a direction which 25 would open the valve 3. The valve or gate 3 may be so constructed that it tends to stand partially open, so that it may be more easily opened. The pawl 42 prevents it from opening when the oil pressure in tank 36 is low. The pawl 42 may be released 30 from the notch 41 by means of a piston 45 operating in a cylinder 46. The piston 45 is biased in a direction to engage pawl 42 with notch 41 by a spring 47. Rigidly associated with crank 43 is an arm 48 which, 35 through an elastic connection to be described, operates a control finger 49 through a crank 50 operatively associated therewith. The control finger 49 is adapted to engage 40 and disengage a collar 51 here shown as rigidly mounted on the tube 31 of the regulating valve 13. In the position shown in the drawing the control finger 49 has moved the collar 51 to the position *c* corresponding to 45 a position of the regulating valve in which fluid is admitted to cylinder 11 to close the valve 3. The mid position of the collar 51 is indicated by the line *m* and its position when the regulating valve corresponds to 50 the open position of valve 3 is indicated by the line *o*.

The elastic connection between the arm 48 and the control finger 49 includes a rod 52, slidably connected with the crank 50. The 55 rod 52 is provided with end stops 53, 54 and

with intermediate collars 55, 56. A spring 57 surrounds the rod 52 and is disposed between the collar 55 and the crank 50. Similarly a spring 58 surrounds the rod 52 and is disposed between the arm 48 and the end 70 stop 54. When the arm 48 is moved in a clockwise direction it engages collar 56 and collar 55 therefore presses against spring 57 to thereby move crank 50. When arm 48 is moved in a counterclockwise direction 75 spring 58 is compressed and then force is transmitted through end stop 54, rod 52, end stop 53 to crank 50 to move the latter in a clockwise direction.

The admission of fluid under pressure to 80 cylinder 46 is controlled by an electromagnetically operated valve 59 provided with a movable valve element 60 operating in a cylinder 61. A piston-like portion 62 of valve 60, in the position shown, covers a port 63 which is connected with a pipe 64 and through a pipe 65 to the pressure tank 36. A port 66 is here shown above the valve member 62 and this port communicates with a pipe 67 leading to cylinder 46. A passage 69 in valve member 60 through which port 66 may be placed in communication with a pipe 70, provides for drainage when the valve 62 is in its closed position. Drainage is also provided below valve member 60 by means of a drain pipe 71. Pipe 64 may if desired be provided with a hand operated 90 valve 72 which under normal conditions would be open. The valve member 60 is adapted to be raised from the position shown in the drawing to its open position by means of an electromagnet or solenoid 73. The electromagnetically operated valve 59 is adapted to be raised from the position 95 shown in the drawing to its open position by means of an electromagnet or solenoid 73.

The electromagnetically operated valve 59 is controlled by a fluid pressure operated switch, here shown as including stationary contacts 74, 75 provided respectively with spring fingers 76, 77. One of these fingers, 76, is longer than the other for a purpose to be hereinafter set forth. The spring fingers and stationary contacts are engageable 100 by means of a cylindrical or disk-like contact member 78, the spring fingers 76, 77 engaging the contact 78 on the cylindrical surface thereof and the end of the contact 78 being engageable with contacts 74, 75. The contact 78 is loosely mounted between collars 79, 80 on a rod 81. The rod 81 is provided with an end stop 82. A spring 83 is disposed around the rod 81 and acts against the end stop 82 and a cover 84 of a cylinder 105 85 which acts as a closure for the mechanism. The end stop 82 may be raised by means of a piston 86 operating in a hole 87 in a block 88 constituting a cylinder therefor. Fluid under pressure is adapted to be admitted beneath the piston 86 through a pipe 89 connected to pipe 65 and thus to the pressure tank 36. A drain 90 may be provided to drain oil, which has leaked to 110 a point above piston 86. A manually oper- 115 120 125 130

ated valve 91 may be provided in pipe 89, this valve under normal conditions being open.

The switch contact 74 is connected by a conductor 92 to a bus-bar 93 or other source of electrical power. The contact 75 is connected by a conductor 94 to one end of the solenoid 73. A conductor 95 connects the other end of the solenoid through either a switch 96 or a switch 97, through a switch 124 to a bus-bar 103. The switches 96, 124 may be located, if desired, at a point remote from the prime mover. The switch 97 is here shown as adapted to be operated to closed position by means of a float 98. The switch 97 may be responsive to the water level of the water supply for the turbine 1, or to any other predetermined condition.

A switch 99 may be inserted in conductor 95 for the purpose of deenergizing solenoid 73 under desired conditions. The switch 99 may be operated to open position by a magnet 100. This magnet may be energized by the closure of one or more relays responsive respectively to different conditions, or abnormal conditions in the prime mover control system, as for example, overload on the generator driven by the turbine, hot bearings etc.

The turbine is provided with a load limiting device which includes a crank 104 connected to a crank 105 by a lost motion connection. This lost motion connection includes, as here shown, a tubular member 106 connected at one end to the crank 104 and cooperating at the other end in a telescopic manner with a rod 107 pivoted to the crank 105. The rod 107 is provided with an adjustable nut 108 which will determine the amount of motion of crank 104 in a clockwise direction before the end of tube 106 engages the nut 108. The crank 104 is rigidly associated with the bell crank 25 so that when the valve 3 moves in a clockwise direction, that is, as it opens, the crank 104 will move in a clockwise direction to rotate the crank 105 in like manner and therefore the control finger 49 in a direction, in the instance shown, to depress the collar 51. As is obvious, this will in turn, by reason of the control exercised on the regulating valve 13, limit the amount of opening of the valve 3.

In order to prevent leakage of pressure from the tank 36 when the prime mover is shut down, a valve 109 may be interposed in the pipe 35 this valve being biased to its closed position by means of a spring 110. The valve 109 may be forced to its open position by means of a piston 111 operating in a cylinder 112. The admission of operating fluid to the cylinder 112 is controlled by means of a piston valve 113 which closes a port 114 connected by a pipe 115 to cylinder 112 when the pressure in the tank 36 falls to a predetermined amount. For this purpose

the valve 113 is biased to its closed position by means of a suitable spring 117. Fluid under pressure from the tank 36 is admitted to force the valve 113 to its open position through a pipe 118 connected to the tank 36. 70 The cylinder 112 may be drained in a suitable manner as by a connection 116 between the pipe 115 and a passage to a drain pipe in the valve 113.

The operation of the system is as follows. 75 Assuming the position of the parts to be as shown in the drawing and it being desired to start up the prime mover from a distant control station, the switch 96 is thrown to its closed position. The motor 38, being then supplied with current, operates the pump 37 and if the pressure in the tank 36 is low, brings that pressure up to a desired predetermined amount. Inasmuch as the valve 109 is in the drawing shown in its closed position it is assumed that the pressure in the tank 36 has fallen to a predetermined minimum at which the valve 113 operates to close valve 109 to cut off communication between tank 36 and regulating valve 13. 80 As the pressure in tank 36 rises above the predetermined minimum, valve 109 opens. Fluid will then be admitted through regulating valve 13 to a cylinder 11 to force the valve 3 to its seat, thereby also relieving the friction between the pawl 42 and the notch 41 so that the pawl 42 is readily releasable. The fluid pressure operated switch 78 may be adjusted so that the force of its restraining spring 83 will be overcome at a pressure somewhat higher than that at which valve 109 is opened. When this predetermined pressure has been reached in tank 36 the piston 86 begins to rise and spring contact finger 76 frictionally engages the contact 78 and temporarily stops the upward movement of contact 78. As the pressure rises still further the stationary friction between finger 76 and contact 78 is overcome more or less suddenly and contact 78 moves a short 85 distance toward its closed position. This cycle of operations is repeated until contact 78 is fully in contact with stationary contacts 74, 75. The arrangement is therefore such that the contact 78 is raised by a series 90 of jerks so that it will bridge the contact fingers 76, 77 with a quick movement.

When contact 78 closes the circuit of solenoid 73, the valve member 60 is raised so that port 63 is placed in communication with port 66 and fluid pressure is therefore admitted to cylinder 46 which raises piston 45 against the action of spring 47. Crank 43 is rotated in a clockwise direction and arm 48 operates to move the control finger 49 away 120 from the collar 51 so that the tube 31 may rise under the action of spring 28. When the spring 28 has brought the regulating valve members 14, 15 to their mid position, the pawl 42 is well out of the notch 41. Con- 125

tinued releasing movement of control finger 49 permits spring 28 to move the regulating valve to its "open" position in which communication between the pipe 35 and pipe 17 is cut off and communication between pipe 35 and pipe 18 is established thereby admitting fluid to cylinder 12 and gradually moving piston 9 in a direction to open the valve 3 to thereby start the turbine. As the valve 3 moves toward its open position the tube 106 of the load limiting device will be moved toward engagement with the adjustable nut 108 and the upward travel of the collar 51 will be limited to an extent dependent upon the position of the nut 108. It will be noted that even though piston 45 has been raised to a limiting position to move the control finger 49 in a counter-clockwise direction, the load limiting means may, depending upon the adjustment, return the control finger 49 in a clockwise direction a predetermined amount inasmuch as the crank 50 will then compress spring 57, the end of crank 50 having a slidable connection with rod 52. Simultaneously, however, with the operation hereinbefore described the turbine will also be under speed control because as the speed rises the spindle 22 will begin to move downwardly at a predetermined speed and the block 33 at the end of the floating lever 20 will act against spring 120, and through collar 121 acting against the end 29 of tube 31 will move the regulating valve 13 a predetermined amount out of its open position toward its mid position or clear to the "closed" position to properly control the opening of valve 3 in accordance with the speed.

It will therefore be seen that by a single initiating operation the turbine is automatically started and brought to its normal running condition under the control of its governor. It is of course apparent that the operation would be the same if the initiating operation had been the closure of the float actuated switch 97.

If it is desired to stop the turbine, the relay 100 may be energized to open conductor 95, or the switch 124 may be opened. This energization of relay 100 may of course also occur by reason of some abnormal condition in the control system. Opening of conductor 95 of course deenergizes solenoid 73 and the valve member 60 drops (in the instance shown, actuated by gravity) to the position shown on the drawing in which fluid pressure is cut off from cylinder 46. Spring 47 then acts to rotate crank 43 in a counter-clockwise direction and arm 48 acting against spring 58 causes the stop 53 on the rod 52 to rotate the control finger 49 in a clockwise direction to depress the collar 51 so that the regulating valve 13 will be operated to its "closed" position. Fluid will then be admitted to cylinder 11

which will move the piston 8 to close the valve 3. When the collar 40 comes into contact with the underside of the pawl 42 the latter will be swung in a clockwise direction thereby moving the regulating valve 70 a predetermined amount toward its mid position. The supply of fluid under pressure to the servo-motor is thereby restricted and the servo-motor moves the valve 3 at a slower rate thus preventing violent closure 75 thereof. Further movement of the valve 3 toward closed position permits the pawl 42 to snap into the notch 41 again locking the valve in its closed position as shown in the drawing. At the same time the counter-clockwise movement of pawl 42 returns the regulating valve to the position shown in which the port to pipe 17 is fully open thus causing the servo-motor to firmly seat the valve 3. The pawl 42 will then snap into 85 the notch 41 again locking the valve 3 in its closed position as shown on the drawing.

It should be understood that it is not desired to limit the invention to the exact details shown and described, for obvious 90 modifications may occur to persons skilled in the art.

It is claimed and desired to secure by Letters Patent:

1. In combination, a prime mover, means 95 for controlling the admission of operating fluid to said prime mover, a governor, responsive to the speed of said prime mover, for said controlling means, including a servo-motor and a regulating valve therefor, means for holding said regulating valve in a position corresponding to the closed position of said controlling means, means for releasing said holding means including a fluid pressure operated device, an 100 electromagnetically operated valve for controlling said fluid pressure operated device, a source of fluid under pressure including an electrically operated pump, means responsive to said fluid under pressure for 110 controlling said electromagnetically operated valve, and means responsive to a predetermined condition for controlling said electromagnetically operated pump and said electromagnetically operated valve. 115

2. In combination, a prime mover, means for controlling the admission of operating fluid to said prime mover, a governor, responsive to the speed of said prime mover, for said controlling means, including a 120 servo-motor and a regulating valve therefor, means for holding said regulating valve in a position corresponding to the closed position of said controlling means, means for releasing said holding means including a fluid 125 pressure operated device, an electromagnetically operated valve for controlling said fluid pressure operated device, a source of fluid under pressure, means responsive to said fluid under pressure for controlling 130

- said electromagnetically operated valve, and means responsive to a predetermined condition for controlling said electromagnetically operated valve.
6. In combination, a prime mover, means for controlling the admission of operating fluid to said prime mover, a governor for said controlling means including a servomotor and regulating valve, means for releasably holding said servo-motor and said regulating valve in a position corresponding to the closed position of said controlling means, and means for releasing said servomotor and said regulating valve. 70
7. In combination, a prime mover, means for controlling the admission of operating fluid to said prime mover, a governor for said controlling means including a servomotor and regulating valve, means for releasably holding said servo-motor and said regulating valve in a position corresponding to the closed position of said controlling means, and means automatically responsive to a predetermined condition for releasing 80 said servo-motor and said regulating valve. 85
8. In combination, a prime mover, means for controlling the admission of operating fluid to said prime mover, a governor for said controlling means including a servomotor and regulating valve, means for releasably holding said servo-motor and said regulating valve in a position corresponding to the closed position of said controlling means, a source of fluid under pressure, and means automatically responsive to a predetermined pressure of said source and another predetermined condition for releasing 90 said servo-motor and said regulating valve. 95
9. In combination, a prime mover, means for controlling the admission of operating fluid to said prime mover, a governor for said controlling means including a servomotor, means for releasably holding said servo-motor in a position corresponding to 100 the closed position of said controlling means, a source of fluid under pressure for supplying said servo-motor, and means operable when said fluid pressure reaches a predetermined amount for releasing said holding 105 means. 110
10. In combination, a prime mover, means for controlling the admission of operating fluid to said prime mover, a governor for said controlling means including a servomotor and regulating valve, means for releasably holding said servo-motor and said regulating valve in a position corresponding to the closed position of said controlling means, a source of fluid under pressure for 115 supplying said servo-motor through said regulating valve whereby said controlling means is forced to a closed position when said pressure reaches a predetermined amount and means responsive to said predetermined pressure, for releasing said holding means. 120
11. In combination, a prime mover, means for controlling the admission of operating fluid to said prime mover, said operating 125 means
12. In combination, a prime mover, means for controlling the admission of operating fluid to said prime mover, a governor for said controlling means including a servomotor and regulating valve, means for releasably holding said servo-motor and said regulating valve in a position corresponding to the closed position of said controlling means, a source of fluid under pressure for supplying said servo-motor through said regulating valve whereby said controlling means is forced to a closed position when said pressure reaches a predetermined amount and means responsive to said predetermined pressure, for releasing said holding means. 130

- fluid tending to open said controlling means when the latter is in a closed position, means for operating said controlling means to closed and open positions, means for reasonably holding said operating means in closed position, and means for compensating for the pressure of said operating fluid on said controlling means before said holding means is operated to released position.
12. In combination, a prime mover, means for controlling the admission of operating fluid to said prime mover, a governor for said controlling means including a servomotor and regulating valve, a source of fluid under pressure for supplying said servomotor through said regulating valve, means operatively associated with said regulating valve for automatically causing said governor to start said prime mover from rest including an electromagnetically operated valve for controlling said fluid under pressure and means responsive to said pressure for closing a switch in the circuit of said electromagnetic valve, and means for maintaining said switch closed until said pressure falls to a predetermined minimum.
13. In combination, a fluid pressure operated motor, electromagnetically-controlled fluid-pressure-actuated controlling means therefor, a source of supply of fluid pressure, means responsive to a rise in pressure of said fluid to a predetermined amount for closing a switch in the circuit of said electromagnetically controlled controlling means, and means for then maintaining said switch closed until said pressure falls to a predetermined amount.
14. In combination, a power supply and control system including a prime mover, means for automatically starting and stopping said prime mover, including a fluid pressure operated motive device, a source of supply of fluid under pressure for said motive device, electromagnetic means for controlling the supply to said motive device, and means responsive to a predetermined abnormal condition in said system for controlling said electromagnetic means.
15. In combination, a prime mover, means for controlling the admission of operating fluid to said prime mover, a fluid pressure operated motive device for operating said admission controlling means, a source of supply of fluid under pressure other than said operating fluid, a connection between said source and said motive device, a regulating valve for controlling the movements of said motive device interposed in said connection, a shut-off valve interposed in said connection between said regulating valve and said source, and means responsive to the fluid pressure of said source for causing said shut-off valve to close at a predetermined minimum pressure.
16. In combination, a prime mover, means for controlling the admission of operating fluid to said prime mover, a fluid pressure operated motive device for operating said admission controlling means, a source of supply of fluid under pressure, a connection between said source and said motive device, a regulating valve for controlling the movements of said motive device interposed in said connection, a shut-off valve interposed in said connection between said regulating valve and said source, means responsive to the fluid pressure of said source, and means operatively associated with said fluid pressure responsive means for causing said shut-off valve to close at a predetermined minimum pressure.
17. In combination, a prime mover, means for controlling the admission of operating fluid to said prime mover, a fluid pressure operated motive device for operating said admission controlling means, a reservoir for fluid under pressure, a pump for supplying fluid to and compressing the same into said reservoir, a connection between said reservoir and said motive device, and means responsive to a predetermined pressure in said reservoir for opening said connection and for interrupting said connection at a predetermined lower pressure.
18. In combination, a prime mover, means for controlling the admission of operating fluid to said prime mover, a fluid pressure operated motive device for operating said admission controlling means, a source of fluid under pressure other than said operating fluid, for supplying said motive device, means for controlling said motive device including a regulating valve for controlling the movements of said motive device to cause it to start said prime mover, and means for causing said motive device controlling means including said regulating valve to be effectively actuated dependent upon a predetermined pressure of said supply.
19. In combination, a prime mover, means for controlling the admission of operating fluid to said prime mover, a governor for said controlling means including a servomotor and regulating valve, a source of fluid under pressure for supplying said servomotor through said regulating valve, means operatively associated with said regulating valve for automatically causing said governor to start said prime mover from rest including an electromagnetically operated valve for controlling said fluid under pressure and means responsive to said pressure for closing a switch in the circuit of said electromagnetic valve.
20. In combination, a prime mover, means for controlling the admission of operating fluid to said prime mover, a motive device for operating said admission controlling means, means for controlling the opening and closing movement of said motive device,

means for releasably holding said movement-controlling means in a position corresponding to the closed position of said admission controlling means, and fluid pressure operated means for releasing said holding means to free said movement-controlling means to thereby start said prime mover.

21. In combination, a prime mover, means for controlling the admission of operating fluid to said prime mover, a motive device for operating said admission controlling means, means for controlling the opening and closing movement of said device, means for moving said movement controlling device to all positions in a predetermined range, means for biasing said movement controlling means independently of said last named means to a position corresponding to the closed position of said admission controlling means, and fluid pressure operated means for overcoming said bias to free said movement-controlling means for movement to all of its positions including that corresponding to the open position of said admission controlling means whereby when fluid pressure is cut off from said fluid pressure operated means said biasing means causes said movement-controlling means to stop said prime mover.

22. In a prime mover control system, means for controlling the admission of operating fluid to said prime mover, a servo-motor and a regulating valve therefor for operating said admission controlling means, means for moving said regulating valve to a position to cause said servo-motor to move said admission controlling means toward closed position at a predetermined speed, and means operatively associated with the movable portion of said servo-motor and said regulating valve for partially closing said regulating valve when said admission controlling means approaches the closed position to thereby reduce said speed.

23. In a prime mover control system, means for controlling the admission of operating fluid to said prime mover, a servo-motor, having a movable element with a notch therein, and a regulating valve therefor, for operating said admission controlling means, a latch cooperable with said notch adapted to releasably hold said element in a position corresponding to the closed position of said admission controlling means, means for biasing said latch toward latched position, and a connection between said latch and said regulating valve.

24. In a prime mover control system, means for controlling the admission of operating fluid to said prime mover, a servo-motor, having a movable element including a collar having a notch, and a regulating valve therefor, for operating said admission controlling means, a latch cooperable with said notch adapted to releasably hold said

element in a position corresponding to the closed position of said admission controlling means, means for biasing said latch toward latched position, and a connection between said latch and said regulating valve, whereby when said servo-motor moves said admission controlling means from an open position toward closed position said collar will move said latch to thereby cause said regulating valve to partially close, further movement permitting said latch to enter said notch to permit said regulating valve to assume the open position thereof in which the servo-motor acts to close the admission controlling means.

25. In a prime mover control system, means for controlling the admission of operating fluid to said prime mover, means for operating said admission controlling means, means whereby said operating means is caused to apply a predetermined force to move said admission controlling means from an open position toward the closed position at a predetermined speed, and means for causing a predetermined decrease in said applied force when said admission controlling means approaches the closed position, and for thereafter again increasing said applied force.

26. In combination, a prime mover, means for controlling the admission of operating fluid to said prime mover, said operating fluid tending to open said admission controlling means when the latter is in the closed position, a fluid pressure operated motive device for operating said admission controlling means to its closed position and adapted to hold it in said position when the pressure of said pressure fluid is above a predetermined amount, and means adapted to prevent the opening of said admission controlling means independently of said motive device.

27. In combination, a prime mover, means for controlling the admission of operating fluid to said prime mover, said operating fluid tending to open said admission controlling means when said latter is in closed position, a speed governor for said prime mover including a fluid pressure operated servo-motor for operating said admission controlling means to its closed position and its open position and adapted to hold it in the closed position when the pressure of said pressure fluid is above a predetermined amount, and latch means adapted to prevent the opening of said admission controlling means independently of said servo-motor.

28. In combination, a prime mover, means for controlling the admission of operating fluid to said prime mover, fluid pressure operated motive means for operating said admission controlling means, a source of fluid under pressure for supplying said motive means including a tank, a pump for putting

- the fluid in said tank under pressure and a motor for said pump, means for controlling said motor, and means for conserving the pressure in said tank upon stoppage of said motor.
29. In combination, a prime mover, means for controlling the admission of operating fluid to said prime mover, fluid pressure operated motive means for operating said admission controlling means, a source of fluid under pressure for supplying said motive means including a tank, a pump for putting the fluid in said tank under pressure and a motor for said pump, means for controlling said motor, a shut-off valve between said source and said motive means, and means for closing said valve in response to a predetermined reduction in pressure of said source.
30. In combination, a prime mover, means for controlling the admission of operating fluid to said prime mover, a servo-motor for operating said admission controlling means, regulating means for said servo-motor biased toward a position corresponding to the open position of said admission controlling means, means responsive to the speed of said prime mover for controlling said regulating means, means for releasably holding said regulating means against said bias in a position corresponding to the closed position of said admission controlling means independently of control by said speed responsive means, means for removing said holding means to thereby free said regulating means for movement throughout its range to thereby permit said servo-motor to operate said admission controlling means toward open position, and means for controlling the rate of acceleration of said prime mover.
31. In combination, a prime mover, means for controlling the admission of operating fluid to said prime mover, a servo-motor for operating said admission controlling means, regulating means for said servo-motor biased toward a position corresponding to the open position of said admission controlling means, means responsive to the speed of said prime mover for controlling said regulating means, means for releasably holding said regulating means against said bias in a position corresponding to the closed position of said admission controlling means independently of control by said speed responsive means, means for removing said holding means to thereby free said regulating means for movement throughout its range to thereby permit said servo-motor to operate said admission controlling means toward open position, and means associated with said admission controlling means and said regulating means for controlling the rate of acceleration of said prime mover.
32. In combination, a prime mover, means for controlling the admission of operating fluid to said prime mover, a servo-motor for operating said admission controlling means, a floating lever, means responsive to the speed of said prime mover for controlling said floating lever, regulating means for said servo-motor having a lost motion connection to said floating lever, means for biasing said regulating means toward a position corresponding to the open position of said admission controlling means, means for releasably holding said regulating means against said bias in a position corresponding to the closed position of said admission controlling means independently of said floating lever, means for removing said holding means to thereby free said regulating means for movement throughout its range to thereby permit said servo-motor to operate said admission controlling means toward open position, a connection between said admission controlling means and said floating lever, and a dash pot interposed in said connection.
33. In combination, a prime mover, means for controlling the admission of operating fluid to said prime mover, a servo-motor for operating said admission controlling means, means for releasably holding said admission controlling means in its closed position independently of said servo-motor, regulating means for said servo-motor biased toward a position corresponding to the open position of said admission controlling means, means responsive to the speed of said prime mover for controlling said regulating means, means for releasably holding said regulating means against said bias in a position corresponding to the closed position of said admission controlling means independently of control by said speed responsive means, means for removing said holding means to thereby free said regulating means for movement throughout its range to thereby permit said servo-motor to operate said admission controlling means toward open position, and means for controlling the rate of acceleration of said prime mover.
34. In combination, a prime mover, means for controlling the admission of operating fluid to said prime mover, said operating fluid tending to open said admission controlling means when the latter is in the closed position, a fluid pressure operated motive device for operating said admission controlling means to its closed position and adapted to hold it in said position when the pressure of said pressure fluid is above a predetermined amount, a source of fluid under pressure for supplying said fluid pressure operative motive device, a valve interposed between said source and said motive device, means responsive to the predetermined pressure of said pressure fluid for causing closure of said valve, and means adapted to prevent the opening of said admission controlling means independently of said motive device.

35. In a prime mover control system, means for controlling the admission of operating fluid to said prime mover, means for operating said admission controlling means, means whereby said operating means is caused to produce a predetermined force to move said admission controlling means from an open position toward the closed position at a predetermined speed, and means for causing a predetermined decrease in said produced force when said admission controlling means approaches the closed position.
36. In combination, a prime mover, means for controlling the admission of operating fluid to said prime mover, a servo-motor for operating said admission controlling means, regulating means for said servo-motor, means responsive to the speed of said prime mover for controlling said regulating means, auxiliary means whereby said regulating means may be moved into a position corresponding to the closed position of said admission controlling means independently of control by said speed responsive means to thereby stop said prime mover, and means operable by fluid under pressure for controlling said auxiliary means.
37. In combination, a prime mover, means for controlling the admission of operating fluid to said prime mover, a servo-motor for operating said admission controlling means, regulating means for said servo-motor, means responsive to the speed of said prime
35. In a prime mover control system, means for controlling the admission of operating fluid to said prime mover, means for operating said admission controlling means, means whereby said operating means is caused to produce a predetermined force to move said admission controlling means from an open position toward the closed position at a predetermined speed, and means for causing a predetermined decrease in said produced force when said admission controlling means approaches the closed position.
36. In combination, a prime mover, means for controlling the admission of operating fluid to said prime mover, a servo-motor for operating said admission controlling means, regulating means for said servo-motor, means responsive to the speed of said prime mover, a connecting means between said speed responsive means and said regulating means, for biasing said connecting means to a position in which said speed responsive means may control said regulating means freely in accordance with the speed of said prime mover, and means including a pressure fluid operated motive device for controlling the position of said regulating means independently of control by said speed responsive means whereby said prime mover may be started or stopped.
37. In combination, a prime mover, means for controlling the admission of operating fluid to said prime mover, a servo-motor for operating said admission controlling means, regulating means for said servo-motor, means responsive to the speed of said prime

35. In a prime mover control system, means for controlling the admission of operating fluid to said prime mover, means for operating said admission controlling means, means whereby said operating means is caused to produce a predetermined force to move said admission controlling means from an open position toward the closed position at a predetermined speed, and means for causing a predetermined decrease in said produced force when said admission controlling means approaches the closed position.

36. In combination, a prime mover, means for controlling the admission of operating fluid to said prime mover, a servo-motor for operating said admission controlling means, regulating means for said servo-motor, means responsive to the speed of said prime mover, a connecting means between said speed responsive means and said regulating means, for biasing said connecting means to a position in which said speed responsive means may control said regulating means freely in accordance with the speed of said prime mover, and means including a pressure fluid operated motive device for controlling the position of said regulating means independently of control by said speed responsive means whereby said prime mover may be started or stopped.

37. In combination, a prime mover, means for controlling the admission of operating fluid to said prime mover, a servo-motor for operating said admission controlling means, regulating means for said servo-motor, means responsive to the speed of said prime

35. In testimony whereof, the signatures of the inventors are affixed hereto.

JOSEPH J. RING.
CARL SCHINDLER.
